UNITED STATES PATENT OFFICE.

JAMES L. BAILEY, OF ST. AUGUSTINE, FLORIDA, ASSIGNOR OF ONE-HALF TO JOHN T. HAMILTON, OF POMPANA, FLORIDA.

SWITCH.

No. 893,970.

Specification of Letters Patent.

Patented July 21, 1908.

Application filed February 25, 1908. Serial No. 417,672.

To all whom it may concern:

Be it known that I, JAMES L. BAILEY, a citizen of the United States, and a resident of St. Augustine, in the county of St. John and State of Florida, have invented a new and Improved Switch, of which the following is a full, clear, and exact description.

This invention relates to switches, and more particularly to railroad switches having movable switch points, and a swinging switch rail or frog.

An object of the invention is to provide a simple, strong and efficient switch for use in connection with railway lines and the like, which has movable switch points, and a swinging switch rail or frog which can be locked in a plurality of positions, from the switch stand.

A further object of the invention is to provide a switch of the class described, in which the swinging rail or frog can be operated from the switch stand, and at the same time locked in a plurality of positions from the switch stand.

25 A still further object of the invention is to provide a switch of the class described in which the swinging rail or frog is locked or clamped in position to avoid pounding, hammering and excessive wear when a train is passing over the switch.

Another object of the invention is to provide a switch of the class described which includes a derailing device operable from the switch stand, and serving to prevent rolling stock from passing from a siding over the switch, when the latter is closed, that is, when the switch is arranged to permit a train to move along the main track without passing on to the siding.

40 The invention consists in the construction and combination of parts to be more fully described hereinafter and particularly set forth in the claims.

Reference is to be had to the accompanying drawings forming a part of this specification, in which similar characters of reference indicate corresponding parts in all the views, and in which

Figure 1 is a plan view of the switch of my invention, showing the swinging rail or frog in different positions in full and dotted lines; Fig. 2 is an enlarged plan view of a portion of the switch showing in detail the swinging rail or frog; Fig. 3 is an enlarged side elevation showing one end of the swinging rail or frog; Fig.

4 is a similar view, showing the central or pivoted portion of the frog; Fig. 5 is an enlarged plan view of a rail chair; Fig. 6 is an end elevation of the chair; Fig. 7 is a transverse section on the line 7—7 of Fig. 3; Fig. 8 is a similar section on the line 8—8 of Fig. 4; Fig. 9 is an enlarged elevation of the switch stand; Fig. 10 is an enlarged cross section of a detail; and Fig. 11 is a plan view showing the derailing device and the mechanism for operating the same.

Before proceeding to a more detailed explanation of my invention it should be clearly understood that when the term "closed" is used with reference to the switch, it is intended to signify thereby that the switch is so arranged that a train can travel along the main track without entering the siding. When the term "open" is used with reference to the switch it is meant that the switch is so arranged that a train will pass from the main track to the siding, and from the siding to the main track. The derailing device which I employ is of service in preventing rolling stock from accidentally passing from the siding to the main track when the switch is closed, and thereby doing injury to the swinging rail or frog. When the switch is open, the derailing device must of course be inoperative, and to avoid the necessity for specially operating the derailing mechanism I provide means for actuating it from the switch stand itself.

My invention resides, primarily, in the arrangement of the swinging rail, the provision of the derailing device, the construction and the arrangement of the mechanism for simultaneously throwing and locking the frog and operating the derailing device, and in the arrangement of the details of construction to carry out this particular purpose.

Referring more particularly to the drawings, 12—12 represent the usual cross-ties or sleepers of wood or any other suitable material. The track and other rails are secured to the ties in any preferred or common manner, for example, as is ordinarily done, by means of spikes. The outer main track rail 13 is continuous, while the inner main track rail 14 has a gap in which is arranged a swinging rail or frog 15, as will appear more clearly hereinafter. The switch point 16 is located between the main track rails and has one end carried by a chair 17 which also supports the inner main rail 14 at one end of the gap.

The inner main rail is formed into a further switch point 18 joined rigidly with the point 16 by means of the usual cross rods 19. A chair 20 similar to the chair 17 carries the end of the main rail at the end of the gap opposite to the chair 17, and similarly carries the end of the inner siding rail 21. The outer siding rail 22 merges with the inner main rail 14 in the usual manner. The switch points 16 and 18 are operated from the switch stand 23 by means of a suitable connecting mechanism 24 in the usual manner. The switch stand is mounted upon certain extended ties, and comprises a base 25 having a target standard 26, a locking lever 27 and a ground weight lever 28. The latter, at the end, has the usual weight 29. The levers 27 and 28 are pivoted upon a pin or shank 30 extending laterally from the switch stand.

20 A base 31 fashioned from cast iron or other suitable material is mounted upon a tie 12 near the center of the gap in the inner main rail 14. The base 31 has an upwardly disposed seat 32 preferably of circular cross-section and formed to receive a correspondingly formed socket 33. The seat and the socket have registering openings therethrough in which is arranged a pivot bolt 34 having its head 35 countersunk in a suitably extended portion of the opening in the socket. A nut 36 serves to secure the bolt in position and the parts together. The base 31 is laterally extended and is secured to the tie by means of bolts, rivets or spikes, or in any other convenient manner. The socket 33 has formed upon the upper face thereof, rail clamps 37 by means of which the swinging rail or frog is secured to the socket. Bolts 38 arranged in suitable registering openings of the clamps and the frog serve to secure the latter firmly in place. The socket embraces the seat at the sides thereof and has its lower rim resting upon the base, thereby preventing dirt or other material from working its way between the bearing surfaces.

At each end of the frog 15 are mounted brackets 39 having clamping members 40 arranged at each side of the frog, and secured in position by means of bolts 41. The brackets 39 have shelf extensions 42 projecting underneath the chairs 17 and 20. The latter, at the upper faces have rail clamps 43 arranged to engage at each side of the ends of the adjacent rails, and have bolts 44 located in registering openings of the clamps and the rails, to hold the latter in position. The chairs are spiked or otherwise firmly secured to the ties which carry them.

60 Each of the shelf extensions 42 has bearings 45 in which is movably mounted a pintle 46. The latter has one end bifurcated and attached to a rod 47. Each of the latter has pivoted at one end a bell crank lever 48 mounted upon a support 49 carried by

certain of the ties. The bell crank lever 48 adjacent to the switch stand has the arm remote from the arm connected with the rod 47, joined by means of a throw rod 50 with the end of the ground weight lever 28. The same arm of the bell crank lever 48 is connected by means of a link 51 with the arm of the other bell crank lever remote from the other rod 47. Each of the pintles 46 between the bearings 45 has a cam locking member 52 rigid therewith. When the ground weight lever 28 is raised, the rod 50 is operated to swing the bell crank levers 48, and these, in turn, by means of the rods 47, swing the frog upon its pivoting base. In this way, the frog can be disposed to close or open the switch. The arrangement is such that when the ground weight lever is actuated to operate the frog it at the same time correspondingly operates the switch points 16 and 18 through the connecting mechanism 24.

Each of the rods 47 has an opening 53 in which is loosely arranged the end 54 of an arm 55. The latter has its opposite end pivoted in a slot 56 of a lock rod 57. The latter is pivoted to the end of the lever 27 of the switch stand. When the lever 27 is swung in one direction or the other, the lock rod is correspondingly actuated, and serves to rotate the rods 47 by means of the arms 55. The rotation of the rods 47 correspondingly swings the cam locking members 52 into position between lugs 58 formed at the under sides of the chairs 17 and 20, or out from between the lugs. It will be understood that when the locking members are operatively arranged, the frame is locked in position and cannot be displaced from that position without releasing the locking members by means of the lever 27 and the intermediate connecting parts.

The locking members 52 are preferably nearly circular in form and are eccentrically mounted upon the pintles 46. Each of them has a portion cut away to form a key-way, so when the locking members are disposed in certain positions they can pass underneath the lugs to permit the frog to be operated. When the locking members are swung into a locking position, they engage, furthermore, at the under side of the chairs and effect a cam-like action which draws the ends of the frog firmly into position upon the chairs. In this way the frog is securely locked in position, and rattling and hammering of the same is obviated together with the wear of the parts, incident thereto.

Any preferred or common form of derailing device can be used in connection with my switch. The derailing device shown in Fig. 11 is merely used as an example, and includes a derailing rail 59 integral with the outer siding rail 22, and outwardly disposed, so that when the derailing point 60 is out of engagement with the rail 22, a car, in travel-

ing along the siding will be displaced from the rails by the rail 59. A support 61 is carried by ties 12 and has pivotally mounted thereupon a bell crank lever 62, connected by means of a rod 63, with a bell crank lever 48. A link 64 connects the bell crank lever 62 with the derailing point 60. The arrangement is such that when the switch is closed the derailing point 60 is separated from the rail 22 and the derailing device is thereby rendered operative. Consequently, if a car should accidentally roll along the siding it would be derailed before it could come into contact with the frog to displace or otherwise injure it. When the switch stand is operated to open the switch, the derailing device is simultaneously operated through the rod 63, the bell crank lever 62 and the link 64, so that the derailing point 60 is swung inward against the rail 22 to permit a car to pass from the siding to the main track without derailment.

To enable the rods 47 to turn freely, they are provided with pivoted heads 50^a by means of which the rods are connected to the bell crank levers 48. Between the switch stand and the rods 47, the rod 50 and the lock rod 57 have joints 51^a and 57^a, respectively, to permit the full movement of the rods 47 transversely of the rod 50 and the lock rod 57.

Having thus described my invention, I claim as new, and desire to secure by Letters Patent:

35. 1. In combination, a track having a plurality of rail gaps, a movable frog adapted to bridge each of said gaps, means for swinging said frog from one of said gaps to another of said gaps, and means for operating said 40 means to clamp said frog in position in any of said gaps.

2. In combination, track rails having the ends separated, a movable frog arranged to connect the ends of said separated rails, movable switch points, means for simultaneously operating said points and said frog, and means for operating said first means to clamp said frog in position at the ends of said separated rails.

50. 3. In combination, a main track, a siding, movable switch points, a movable frog, means for simultaneously operating said points and said frog, means for locking said frog in a plurality of positions, a derailing device, and means controlled by said first means, for operating said derailing device.

4. In combination, a main track, a siding, a switch stand, movable switch points, a switching frog, said siding having a derailing device, means for simultaneously operating said points and said frog from said stand, means for locking said frog in a plurality of positions from said stand, and means, controlled by said operating means, for operat-

ing said derailing device, said derailing device being operative when said switch is closed.

5. In combination, a main track, a siding, movable switch points, a movable frog, means for simultaneously operating said points and said frog, and means for operating said first means whereby the ends of said frog are depressed to clamp said frog in a plurality of positions.

6. In combination, a main track, a siding, movable switch points, a swinging frog, a switch stand, means for simultaneously operating said points and said frog from said stand, and means operable from said stand for disposing said first means to clamp said frog in a plurality of positions.

7. In combination, a main track, a siding, movable switch points, a swinging frog, means for simultaneously operating said points and said frog, and means for locking and clamping said frog in a plurality of positions the clamping being effected by depressing the ends of said frog.

8. In combination, main rails, siding rails, movable switch points, one of said main rails and one of said siding rails each having a gap, a swinging frog arranged in said gaps and adapted to bridge the same, means for simultaneously operating said points and said frog, and means for simultaneously locking said frog in position bridging one of said gaps, and for clamping said frog in said bridging positions.

9. In combination, main rails, siding rails, a switch stand, movable switch points, one of said main rails and one of said siding rails each having a gap, a swinging frog arranged to bridge said gaps, means for simultaneously operating said points and said frog from said stand, and means for locking said frog in a plurality of positions each bridging one of said gaps, said frog, when locked in position, having its ends clamped with respect to the adjacent ends of the main rail or siding rail.

10. In a device of the class described, a swinging frog having brackets at the ends adapted to be arranged adjacent to rail ends, means secured to said brackets for swinging said frog and operable from a switch stand, and means for operating said first means to clamp the ends of said frog in position adjacent to the rail ends.

11. In a device of the class described, a base having a seat, a socket movably mounted upon said seat, said socket having clamping members, and a frog rail mounted in position between said clamping members, said socket extending at the sides of said seat and embracing the same.

12. In a device of the class described, a base plate having an upwardly disposed seat, a socket movably mounted upon said seat and having the sides movably engaging said

base plate at the sides of said seat, said socket and said seat having registering openings, a pivot bolt mounted in said openings, said socket having at the upper face clamping flanges formed to engage at the sides of a rail, and a frog rail mounted between said clamping flanges.

13. In a device of the class described, a rail having a gap, chairs carrying the ends of said rail at said gap, said chairs extending into said gap, a pivoted frog mounted in said gap and adapted to have its ends resting upon the extending chairs, means for operating said frog, and means for clamping the ends of said frog in position upon said chairs.

14. In a device of the class described, a rail having a gap, chairs carrying the ends of said rail at said gap and extending into said gap beyond the rail ends, a frog pivoted in said gap and adapted to have its ends disposed upon said extending chairs to bridge said gap, said frog at the ends having brackets provided with extensions adapted to project under said chairs, members carried by said brackets and adapted to be jammed against said chairs at the under sides thereof, means for operating said members from a remote point, and means for operating said frog.

15. In a device of the class described, a rail having a gap, chairs carrying the ends of said rail at said gap, each of said chairs projecting into said gap and comprising a plate having at the upper side clamping flanges adapted to engage rail ends, each of said chairs further having lugs at the under side of the part projecting into said gap, a swinging frog adapted to bridge said gap and having means for removably engaging said lugs to lock said frog in position, and means for operating said frog from a remote point.

16. In a device of the class described, a rail having a gap, chairs carrying the ends of said rail at said gap, each of said chairs comprising a plate having at the upper side clamping flanges adapted to engage a rail end, said chairs projecting into said gap, each of said chairs further having lugs at the under side of the part projecting into said gap, a frog pivoted in said gap and adapted to have the ends disposed upon the extended portions of said chairs, said frog having at the ends brackets provided with clamping flanges adapted to engage at the sides of the frog, and further having extensions adapted to project under said chairs, cam members pivoted upon said extensions and adapted to engage said lugs to lock said frog in position, said cam members further being adapted to engage said chairs to clamp the ends of said frog upon the chairs, means for operating

said frog, and means for operating said cam members.

17. In a device of the class described, a rail having a gap, chairs carrying the ends of said rail at said gap and projecting into said gap, a frog pivoted in said gap and having brackets projecting under said chairs when said frog bridges said gap, said brackets having pintles provided with cam members 70 adapted to engage said chairs to lock said frog in position and to clamp the ends of said frog against said chairs, rods secured to said pintles, a switch stand having a lever, a throw-rod connecting said lever and said rods 75 and serving to swing said frog when said lever is operated, said stand having a further lever, and a locking rod connecting said further lever and said rods, whereby said rods can be rotated to operate said cam 80 members when said further lever is operated.

18. In a device of the class described, a rail having a gap, a swinging frog arranged to bridge said gap, said frog having rotatable members serving to lock said frog in position 85 and to clamp the ends thereof at the ends of said gap, rods connected with said rotatable members, a switch stand having a lever, a throw-rod connecting said lever and said rods to permit said frog to be swung when 90 said lever is operated, said stand having a further lever, said rods having arms, and a locking rod connecting said arms and said further lever, to permit said rods to be rotated to operate said members when said 95 further lever is operated.

19. In a device of the class described, a main rail and a siding rail, each having a gap, a swinging frog adapted to bridge said gaps, said frog having rotatable members adapted 100 to clamp the ends of said frog in position at the ends of said gaps, rods secured to said rotatable member, bell crank levers secured to said rods, said bell crank levers being operatively connected, a switch stand having a lever, a throw-rod connecting one of said bell crank levers and said levers, said 105 rods having arms, said switch stand having a further lever, a locking rod connecting said arms and said further lever, a derailing device, and means for operatively connecting said derailing device and one of said bell 110 crank levers, whereby said derailing device is inoperative when said frog bridges said gap of said siding rail.

In testimony whereof I have signed my name to this specification in the presence of two subscribing witnesses.

JAMES L. BAILEY.
